[57] CLAIM

The ornamental design for bumper facade for motor vehicles, as shown and described.

DESCRIPTION

FIG. 1 is a perspective view of a bumper facade for motor vehicles showing my new design;

FIG. 2 is a top plan view thereof;

FIG. 3 is a front elevation view thereof;

FIG. 4 is an elevation view taken from one end thereof;

FIG. 5 is a bottom plan view thereof;

FIG. 6 is a rear elevation view thereof;

FIG. 7 is a perspective view of an alternative embodiment of my design for a bumper facade including a license plate holder;

FIG. 8 is a top plan view thereof;

FIG. 9 is a front elevation view thereof;

FIG. 10 is an elevation view taken from one end thereof;

FIG. 11 is a bottom plan view thereof; and,

FIG. 12 is a rear elevation view thereof.

It should be appreciated that the mirror images of FIG. 4 and FIG. 10 are elevation views of the opposite ends thereof.
